Dec. 126

North, Harrison & Co. Philadelphia Pa.
Assignees of J. W. Gibbs Albany, New York. Letters
Patent No. 226, dated July 10, 1849.

The Schedule referred to in these Letters Patent and making part of the same.

To all whom it may concern: Be it known that I, Samuel W. Gibbs of Albany, in the County of Albany, and State of New York, have invented or produced a new design for cooking Stoves, of which the following is a full and exact description:

126

The design consists of a combination of mouldings, ornaments, and plates, represented in the drawings accompanying this specification. The said drawings are numbered and lettered for reference, as follows, to wit:

Fig. 1 represents a side view of the stove as designed by me, showing one of the doors to the fire box, two of the oven doors, and the summer hearth.

Fig. 2. A front view, exhibiting the front doors of the fire box and a front view of the summer hearth.

Fig. 3. A view of the back plate, together with such other portions of the stove as are embraced in a back view.

Fig. 4. A view from above the stove, exhibiting the top plate, covers, and the top of the summer hearth.

a. Moulding around the edge of the top plate.

b, c, and d. Moulding around the oven doors and the doors of the fire box.

e. Moulding around the top plate of the summer hearth, - the said top plate together with the covers, being detached from the hearth.

f. Moulding around the summer hearth.

My claim is limited to the design, as represented in the foregoing specification.

In witness whereof I have hereunto set my hand and affixed my seal, this ninth day of December A. D. one thousand eight hundred and forty eight.
